ABSTRACT

In a color cathode ray tube comprising a color screen having arrays of different color phosphors, beam selecting means provided with passages corresponding to the arrays of color phosphors, plural-beam generating means for directing a plurality of electron beams in a common plane toward the screen for impingement on respective phosphors of the arrays through the corresponding passages, and a deflecting means for causing the plurality of electron beams to scan on the screen and including a pair of deflection coil means connected in parallel to each other for generating nonuniform magnetic fields; misconvergence of the beams is corrected by a device including variable impedance means connected in series to at least one of the deflection coil means for adjustably controlling the magnetic field produced thereby.

MISCONVERGENCE COMPENSATING DEVICE FOR COLOR CATHODE RAY TUBES

BACKGROUND OF THE INVENTION

1. Field of the Invention

This invention relates to color cathode ray tubes, and more particularly is directed to a misconvergence compensating device for correcting misconvergence of the electron beams in such tubes.

2. Description of the Prior Art

In order to eliminate the misconvergence of the electron beams which results from errors in mounting of the cathodes in a tube envelope, extreme care is required in the mounting of the cathodes. If the cathodes have been mounted eccentrically in the tube envelope, the misconvergence of the electron beams emitted from the cathodes, and which is caused by the eccentric mounting, has been corrected by a coil specially mounted on the neck portion of the tube envelope. Further, some misconvergence may be caused by an error in the mounting of the deflection yoke means on the tube envelope, so that special attention is required in the mounting of the deflection yoke means. Thus, heretofore, extreme care has had to be exercised in assembling the tube to minimize misconvergence and, to the extent that the misconvergence could not be completely avoided by such care, additional devices had to be assembled in the tube.

SUMMARY OF THE INVENTION

In connection with this invention, a color cathode ray tube comprising a color screen having arrays of different color phosphors, beam selecting means provided with passages corresponding to the arrays of color phosphors, beam generating means for directing a plurality of electron beams in a common plane toward the color screen for impingement on respective phosphors of the arrays through the corresponding passages and deflecting means for causing the electron beams to scan the color screen and including a pair of deflection coil means connected in parallel to each other for generating nonuniform magnetic fields, has misconvergence of the beams corrected by variable impedance means connected to at least one of the deflection coil means for controlling the magnetic field established thereby.

Accordingly, it is an object of this invention to avoid cross-misconvergence of electron beams in color cathode ray tubes.

It is another object of this invention to avoid neck-twist-misconvergence of electron beams in color cathode ray tubes.

It is still another object of this invention to avoid tilt-misconvergence of electron beams in color cathode ray tubes.

It is a further object of this invention to avoid the aforementioned misconvergences of the beams in color cathode ray tubes that result from magnetic fields established by the deflecting means.

It is still a further object of this invention to avoid the aforementioned misconvergences in color cathode ray tubes that result from magnetic fields of the deflection coils by connecting the latter with variable impedance means.

It is still another object of this invention to provide a misconvergence compensating device for color cath-

ode ray tubes which is simple in construction and easy to handle.

The above, and other objects, features and advantages of this invention will become apparent from the following description of illustrative embodiments which is to be read in conjunction with the accompanying drawings.

BRIEF DESCRIPTION OF THE DRAWINGS

10 FIG. 1 is a schematic sectional view in a horizontal plane passing through the axis of a single-gun, plural-beam color picture tube of the type to which this invention is applied;

15 FIG. 2 is a schematic end elevational view of a deflecting means for the tube of FIG. 1, and showing the pattern of the magnetic lines of flux in the magnetic fields produced by such deflecting means;

20 FIG. 3 is a diagrammatic showing of the electron beams and the magnetic lines of flux in a magnetic field established by a horizontal deflection coil, and to which reference will be made in explaining this invention;

25 FIG. 4 is a diagrammatic representation of the so-called cross-misconvergence on the screen scanned by the electron beams when the latter are improperly positioned as depicted in FIG. 3;

FIG. 5 is a diagrammatic view similar to that of FIG. 3, but showing another form of deviation of the beams from the proper position thereof;

FIG. 6 is a schematic illustration of the so-called 30 twist-misconvergence on the screen scanned by the electron beams positioned as depicted in FIG. 5;

FIG. 7 is a circuit diagram of a deflection means according to this invention for compensating for the misconvergences;

35 FIG. 8 is a sectional view of a variable impedance means that may be employed in the circuit of FIG. 7;

FIGS. 9A and 9B show current waveforms to which reference will be made in explaining the operation of the circuit depicted in FIG. 7;

40 FIG. 10 is a diagrammatic showing of the electron beams and of the magnetic lines of flux in a magnetic field established by a DC current for compensating for the misconvergence shown in FIG. 5;

45 FIG. 11 is a diagrammatic representation of the electron beams which are improperly positioned with respect to the magnetic lines of flux in the magnetic field produced by a vertical deflection coil;

FIG. 12 is a schematic illustration of the so-called tilt-misconvergence on the screen when scanned with the 50 electron beams as shown in FIG. 11;

FIG. 13 is a circuit diagram of a means for compensating for the misconvergence depicted in FIG. 12 according to this invention; and

55 FIG. 14 is a circuit diagram showing another means for compensating for the misconvergence according to this invention.

DESCRIPTION OF THE PREFERRED EMBODIMENTS

60 Referring to the drawings in detail, and initially to FIG. 1 thereof, it will be seen that a single-gun, plural-beam color picture tube 10 to which this invention is applied may be of the type disclosed in detail in U.S. Pat. No. 3,448,316, issued June 3, 1969, and having a common assignee herewith. The tube 10 may comprise a glass envelope (not shown) having a neck and a cone extending from the neck to a color screen S provided

65

with the usual arrays of color phosphors $S_R S_G$ and S_B and with an apertured beam selecting grid or shadow mask G_p . Disposed within the neck is a single electron gun A having cathodes K_R , K_G and K_B which constitute beam-generating sources with the respective beam-generating surfaces thereof disposed as shown in a plane which is substantially perpendicular to the axis of the electron gun. In the embodiment shown, the beam-generating surfaces are arranged in a straight line so that the respective beams B_R , B_G and B_B emitted therefrom are directed in a substantially horizontal plane containing the axis of the gun, with the central beam B_G being coincident with such axis. A first grid G_1 is spaced from the beam-generating surfaces of cathodes K_R , K_G and K_B and has apertures g_{1R} , g_{1G} and g_{1B} formed therein in alignment with the respective cathode beam-generating surfaces. A common grid G_2 is spaced from the first grid G_1 and has apertures g_{1R} , g_{1G} and g_{1B} formed therein in alignment with the respective apertures of the first grid G_1 . Successively arranged in the axial direction away from the common grid G_2 are open-ended, tubular grids or electrodes G_3 , G_4 and G_5 , respectively, with cathodes K_R , K_G and K_B , grids G_1 and G_2 , and electrodes G_3 , G_4 and G_5 being maintained in the depicted assembled positions thereof, by suitable, nonillustrated support means of an insulating material.

For operation of the electron gun of FIG. 1, appropriate voltages are applied to the grids G_1 and G_2 and to the electrodes G_3 , G_4 and G_5 . Thus, for example, a voltage of 0 to minus 400V is applied to the grid G_1 , a voltage of 0 to 500V is applied to the grid G_2 , a voltage of 13 to 20KV is applied to the electrodes G_3 and G_5 , and a voltage of 0 to 400V is applied to the electrode G_4 , with all of these voltages being based upon the cathode voltage as a reference. As a result, the voltage distributions between the respective electrodes and cathodes, and the respective lengths and diameters thereof, may be substantially identical with those of a unipotential-single beam type electron gun which is constituted by a single cathode and first and second, single-apertured grids.

With the applied voltage distribution as described hereinabove, an electron lens field will be established between grid G_2 and the electrode G_3 to form an auxiliary lens L' as indicated in dashed lines, and an electron lens field will be established around the axis of the electrode G_4 , by the electrodes G_3 , G_4 and G_5 , to form a main lens L , again as indicated in dashed lines. In a typical use of electron gun A, bias voltages of 100V, 0V, 300V, 20KV, 200V and 20V may be applied respectively to the cathodes K_R , K_G and K_B , the first and second grids G_1 and G_2 and the electrodes G_3 , G_4 and G_5 .

Further included in the electron gun of FIG. 1 are electron beam convergence deflecting means F which comprise shielding plates P and P' disposed in the depicted spaced relationship at opposite sides of the gun axis, and axially extending, deflector plates Q and Q' which are disposed, as shown, in outwardly spaced, opposed relationship to shielding plates P and P', respectively. Although depicted as substantially straight, it is to be understood that the deflector plates Q and Q' may, alternatively, be somewhat curved or outwardly bowed, as is well known in the art.

The shielding plates P and P' are equally charged and disposed so that the central electron beam B_G will pass substantially undeflected between the shielding plates P and P', while the deflector plates Q and Q' have neg-

5 ative charges with respect to the plates P and P' so that respective electron beams B_B and B_R will be convergently deflected as shown by the respective passges thereof between the plates P and Q and the plates P' and Q'. More specifically, a voltage V_p which is equal to the voltage applied to the electrode G_5 , may be applied to both shielding plates P and P', and a voltaage V_Q , which is some 200 to 300V lower than the voltage V_p , is applied to the respective deflector plates Q and 10 Q' to result in the respective shielding plates P and P' being at the same potential, and to result in the application of a deflecting voltage difference or convergence deflecting voltages between the respective plates P' and Q' and P and Q and it is, of course, this convergence defleciing voltage V_c which will impart the requisite convergent deflection to the respective electron beams B_B and B_R .

20 In operation, the respective electron beams B_R , B_G and B_B which emanate from the beam generating surfaces of the cathodes K_R , K_G and K_B will pass through the respective grid apertures g_{1R} , g_{1G} and g_{1B} , to be intensity modulated with what may be termed the "red," "green" and "blue" intensity modulation signals applied between the said cathodes and the first grid G_1 . 25 The respective electron beams will then pass through the common auxiliary lens L' by which the beams are made to cross each other at the center of the main lens L and to emerge from the latter with beams B_R and B_B diverging from beam B_G . Thereafter, the central electron beam B_G will pass substantially undeflected between shielding plates P and P' since the latter are at the same potential. Passage of the electron beam B_B between the plates P' and Q' and of the electron beam B_R between the plates P and Q will however, result in the convergent deflections thereof as a result of the convergence deflecting voltage applied theretwix, and the system of FIG. 1 is so arranged that the electron beams B_B , B_G and B_R will desirably converge or 30 cross each other at a common spot centered in an aperture or passage between adjacent grid wires g_p of the beam selecting grid or mask G_p so as to diverge therefrom to strike the respective color phosphors of a corresponding array thereof on screen S. More specifically, it may be noted that the color phosphor screen S is composed of a large plurality of sets or arrays of vertically extending "red," "green" and "blue" phosphor stripes or dots $S_R S_G$ and S_B with each of the arrays or sets of color phosphors forming a color picture element as in a chromatron type color picture tube. Thus, 35 it will be understood that the common spot of beam convergence corresponds to one of the thusly formed color picture elements.

40 The voltage V_p may also be applied to the lens electrodes G_3 and G_5 and to the screen S as an anode voltage in conventional manner through a non-illustrated graphite layer which is provided on the inner surface of the cone portion of the tube envelope. The grid wires of screen grid G_p may have a post-focussing voltage ranging, for example, from 6 to 7 KV applied thereto. 45 Thus, to summarize the operation of the depicted color picture tube of FIG. 1, the respective electron beams B_B , B_G and B_R will be converged at screen grid G_p and will diverge therefrom in such manner that electron beam B_B will strike the "blue" phosphor S_B , electron beam B_G will strike the "green" phosphor S_G and electron beam B_R will strike the "red" phosphor S_R of the 50 array or set corresponding to the grid aperture at which

the beams converge. Electron beam scanning of the face of the color phosphor screen is effected by deflecting means comprised of horizontal and vertical deflection coil means indicated in broken lines at 20 and which receives horizontal and vertical sweep signals whereby a color picture will be provided on the color screen. Since, with this arrangement, the respective electron beams are each passed, for focussing, through the center of the main lens L of the electron gun A, the beam spot formed by impingement of the beams on the color phosphor screen S will be substantially free from the effects of coma and/or astigmatism of the said main lens, whereby improved color picture resolution will be provided.

It will be apparent that, when beams B_R , B_G and B_B are deflected by deflecting means 20 from a point of convergence at the center of grid G_p and screen S, as during scanning of the screen, the distances that such beams travel through the deflecting means 20 are relatively varied, that is, the beams undergo different degrees of deflection and this may result in misconvergence of the beams, particularly when the latter are directed at corner portions of the screen.

The misconvergences mentioned above are compensated for by establishing magnetic deflectin fields in the form of a pin cushion and barrel with the deflection coil means 20 as disclosed in the U.S. Pat. No. 3500,114. More specifically, the coil means 20 may comprise a pair of horizontal deflection coils L_{H1} and L_{H2} and a pair of vertical deflection coils L_{V1} and L_{V2} mounted on a picture tube 10 at its neck portion 31, as shown in FIG. 2. In the illustrated example, all the deflection coils are saddle-shaped and the horizontal deflection coils L_{H1} and L_{H2} for producing a pin-cushion-shaped magnetic field H are disposed above and below the neck portion 31 in opposing relation to each other and the vertical deflecion coils L_{V1} and L_{V2} for producing a barrel-shaped magnetic field V are respectively disposed on the left and right sides of the neck portion 31 in opposing relation to each other. The horizontal and vertical deflection magnetic fields H and V established by the deflection coils act on the three electron beams B_R , B_G and B_B simultaneously.

If the gun A and coils L_{H1} , L_{H2} , L_{V1} and L_{V2} are all mounted in exactly the correct positional relationships to each other, the deflection coils are disposed in such a manner that the electron beam B_G may pass through the intersection of the axis of symmetry X—X of the horizontal deflection magnetic field H with the axis of symmetry Y—Y of the vertical deflection magnetic field V and the electron beams B_R and B_B may pass through points on the axis X—X which are symmetrically spaced from the axis Y—Y, thereby to avoid the misconvergence of electron beams.

However, in the event that the three electron beams B_R , B_G and B_B are deviated in the direction of the axis Y—Y away from the axis X—X to a line X'—X' parallel to axis X—X by errors introduced in the mounting of the cathodes K_R , K_G and K_B , as depicted in FIG. 3, a so-called cross-misconvergence is caused on the screen S as depicted in FIG. 4 because the horizontal deflection magnetic field H is pin-cushioned in shape.

In the event that the side electron beams B_R and B_B deviate from the axis X—X in the direction of the axis Y—Y in opposing relation to each other, as shown in FIG. 5, a so-called neck-twist is caused as illustrated in FIG. 6.

This invention has for its object to provide a device

which is simple in construction but capable of electrically correcting or eliminating the cross-misconvergence and neck twist shown on FIGS. 4 and 6.

5 One example of this invention will now be described with reference to FIG. 7.

In accordance with the present invention, variable impedance means, for example, first and second auxiliary coils L_{S1} and L_{S2} are respectively connected in series with the horizontal deflection coils L_{H1} and L_{H2} and are further connected to a horizontal deflection circuit (not shown) through terminals 32A and 32B. These auxiliary coils L_{S1} and L_{S2} are parts of a coil L_S (FIG. 8) wound on a common bobbin 33 in the same direction. A core 34 is movable in the bobbin 33 by a screw 35 to serve as a variable inductance, and the opposite ends of the coil L_S and the mid point therebetween are connected to terminals t_1 , t connected and t_3 so that the coil portion between terminals t_1 and t_2 and that between t_2 and t_3 respectively serve as the coils L_{S1} and L_{S2} . Accordingly, in the illustrated example the deflection coils L_{H1} and L_{H2} are respectively connected at one end to the terminal 32A and at the other end to the terminals t_1 and t_2 of the coil L_S and the terminal t_3 of the coil L_S is connected to the terminal 32B.

Further, a first rectifier D_1 , a variable resistor V_R and a second rectifier D_2 opposite in polarity to rectifier D_1 are connected in series to one another and the resulting series circuit is connected in parallel to the coil L_S and a slider V_a of the variable resistor V_R is connected to the terminal 32B.

With such an arrangement, the cross-misconvergence can be corrected by adjustment of the core 34 of coil L_S and the neck twist can be corrected by adjustment of the variable resistor V_R . That is, if the core of the coil L_S is adjusted, the inductance values of the coils L_{S1} and L_{S2} become different from each other, so that the horizontal deflection current flowing in one of the deflection coils L_{H1} and L_{H2} becomes smaller and the other becomes greater. Therefore, as a result of the adjustment of coil L_S , the axis of symmetry X—X of the horizontal deflection magnetic field H is apparently shifted in the direction of the axis Y—Y in FIG. 3. Thus, the axis of symmetry X—X is brought into agreement with the line X'—X' on which the electron beams B_R , B_G and B_B lie, thereby essentially correcting or eliminating the cross-misconvergence.

50 The coil L_S is supplied with a pulse voltage, such as depicted in FIG. 9A, which is divided from the horizontal deflection voltage. Since this pulse voltage is rectified by the rectifier D_1 , a current I_1 circulates in the coils L_{H1} and L_{H2} (FIG. 7) in the horizontal scanning period t_h (FIG. 9B). Similarly, a current I_2 (FIG. 7) rectified by the rectifier D_2 circulates in the coils L_{H1} and L_{H2} in a direction opposite to the current I_1 . Thus, the coils L_{H1} and L_{H2} are actually supplied with a current I_1 — I_2 which is the difference between the currents I_1 and I_2 as determined by the adjustment of the variable resistor V_R , thus correcting for certain deviations of the electron beams. More specifically, in order to compensate for the neck twist shown in FIG. 5, the slider V_a of the variable resistor V_R is moved to the left of the center thereof, thereby to decrease the value of its resistance on the side of the deflection coil L_{H1} . As a result of this, the difference current I_1 — I_2 flows in the direction from the deflection coil L_{H1} to the coil L_S to

provide a magnetic flux Φ such as is depicted in FIG. 10. Consequently, the electron beams B_R and B_B are respectively deflected up and down, as viewed in the figure, and are aligned on the axis X—X.

Since the magnitude and direction of the magnetic flux Φ can be adjusted by changing the magnitude and direction of the difference current $I_1 - I_2$, the magnitude and direction of the magnetic flux Φ are altered by adjusting the variable resistor V_R , thereby correcting the neck twist.

Further, when the electron beams B_R , B_G and B_B are all deviated from their proper positions along the axis X—X, as depicted in FIG. 11, a so-called tilt-misconvergence is generated as shown in FIG. 12.

FIG. 13 illustrates one example of a circuit according to this invention for correcting the tilt-misconvergence. Reference characters L_{V1} and L_{V2} indicate saddle-shaped vertical deflection coils and numerals 36A and 36B identify terminals connected to a vertical deflection circuit (not shown). A variable resistor R is used as a variable impedance element in place of the previously described coil L_s and its slider is connected to the terminal 36B. The reason for employing the variable resistor R is that the vertical deflection circuit is a resistive circuit which is smaller in power consumption than the horizontal deflection circuit and the power dissipation of the variable resistor R is negligible.

With such an arrangement, the adjustment of the variable resistor R causes a difference between the vertical deflection currents flowing in the left and right vertical deflection coils L_{V1} and L_{V2} to provide different magnetic field distributions. For example, when the slider of the variable resistor R is moved to the left of the center thereof, as depicted in FIG. 13, the vertical deflection current flowing in the vertical deflection coil L_{V1} becomes greater than that flowing in the other coil L_{V2} to shift the center of the vertical deflection magnetic field to an axis parallel to axis Y—Y and passing through the position of beam B_G in FIG. 11, so that the three electron beams B_G , B_R and B_B are properly positioned with respect to the center of the magnetic field, thereby to correct the tilt-misconvergence. By connecting the series circuit of the variable resistor V_R and the rectifiers D_1 and D_2 , described with reference to FIG. 7, in parallel to the variable resistor R as depicted in FIG. 13, the misconception resulting from the neck twist can be similarly corrected.

Further, it is also possible to omit the second rectifier D_2 in the circuit of FIG. 7 to simplify it as shown in FIG. 14. In this example, however, the direction of the magnetic flux Φ is reversed by the reversal of the polarity of the rectifier D_1 .

Although the present invention has been described in connection with horizontal and vertical deflection coils which are all saddle-shaped, the invention is also applicable to a color picture tube using toroidal deflection coils. Further, the variable impedance means L_s may be connected to one of the deflection coils, rather than to both coils as described.

It will be apparent that many modifications and variations may be effected without departing from the scope of the novel concepts of this invention.

What is claimed is:

1. In the combination of a color cathode ray tube including a color screen having arrays of different color phosphors, beam selecting means provided with passages corresponding to said arrays of color phosphors,

plural-beam generating means for directing a plurality of electron beams in a common plane toward said screen for impingement on respective phosphors of said arrays through the corresponding passages, and 5 deflecting means for causing said plurality of electron beams to scan said screen and including a source of deflection voltage and a pair of deflection coil means connected in parallel to each other and to said source of deflection voltage for producing a nonuniform magnetic scanning field; the improvement comprising a 10 misconvergence compensating device including impedance means connected in series between at least one of said pair of deflection coil means and said source of deflection voltage, the magnitude of the impedance of 15 said impedance means being selectively adjustable to vary the amount of current from said source of deflection voltage flowing in said one deflection coil means relative to the other deflection coil means for controlling said magnetic field produced thereby.

2. The combination according to claim 1 wherein said variable impedance means includes first and second variable impedance elements respectively connected in series to said one deflection coil means and to the other of said pair of deflection coil means.

25 3. The combination according to claim 2, wherein said first and second variable impedance elements are controlled at the same time.

30 4. The combination according to claim 1, wherein rectifier means and variable resistance means are connected between said pair of deflection coil means.

5. In the combination of a color cathode ray tube including a color screen having arrays of different color phosphors, beam selecting means provided with passages corresponding to said arrays of color phosphors, 35 plural-beam generating means for directing a plurality of electron beams in a common plane toward said screen for impingement on respective phosphors of said arrays through the corresponding passages, and deflecting means for causing said plurality of electron beams to scan said screen and including a source of deflection voltage and a pair of deflection coil means connected in parallel to each other and to said source of deflection voltage for producing a nonuniform magnetic scanning field; the improvement comprising a 40 misconvergence compensating device including impedance means connected in series between at least one of said pair of deflection coil means and said source of deflection voltage, the magnitude of the impedance of said impedance means being selectively adjustable to vary the amount of current from said source of deflection voltage flowing in said one deflection coil means relative to the other deflection coil means for controlling said magnetic field produced thereby, and rectifier 45 means and variable resistance means connected between said pair of deflection coil means, wherein said rectifier means includes a first rectifier connected to one of said pair of deflection coil means and a second rectifier connected to the other of said pair of deflection coil means, and said variable resistance means is 50 interposed between said first and second rectifiers.

6. The combination according to claim 1, wherein said pair of deflection coil means are horizontal deflection coil means for producing a pin-cushion-shaped magnetic field.

7. The combination according to claim 1, wherein said variable impedance means is constituted by variable inductance means.

8. The combination according to claim 1, wherein said pair of deflection coil means are vertical deflection coil means for producing a barrel-shaped magnetic field.

9. The combination according to claim 8, wherein said variable impedance means connected to said vertical deflection coil means is constituted by variable resistance means.

10. In the combination of a color cathode ray tube including a color screen having arrays of different color phosphors, beam selecting means provided with passages corresponding to said arrays of color phosphors, plural-beam generating means arranged in line for directing a plurality of electron beams in a common plane toward the screen for impingement on respective phosphors of the arrays through the corresponding passages, and deflecting means for causing the plurality of electron beams to scan the screen and including first and second sources of deflection voltage and at least a first and a second pair of deflection coils, the deflection coils of the first pair being connected in parallel to each other and to the first source of deflection voltage for producing a pincushioned-shaped magnetic scanning field, the deflection coils of the second pair being connected in parallel to each other and to the second source of deflection voltage for producing a barrel-shaped magnetic scanning field, the improvement comprising cross-misconvergence compensating means including first impedance means connected in series between at least one of the deflection coils of the first pair and the first source of deflection voltage, the magnitude of the impedance of the first impedance means being selectively adjustable to vary the amount of current from the first source of deflection voltage flowing in the one deflection coil relative to the other deflection coil of the first pair for compensating for cross-

misconvergence of the electron beams due to the pincushion shaped magnetic field produced in the first pair of deflection coils and neck twist compensating means including first and second rectifiers and first variable

5 resistance means, the first rectifier being connected to one of the first pair of deflection coils, the second rectifier being connected to the other of the first pair of deflection coils, and the first variable resistance means being connected in series between terminals of like polarity at the first and the second rectifiers and further connected to the first source of deflection voltage for supplying a net rectified current of a predetermined polarity to the first pair of deflection coils.

11. The combination recited in claim 10 further comprising tilt-misconvergence compensating means including second impedance means connected in series between at least one of the deflection coils of the second pair of deflection coils and the second source of deflection voltage, the magnitude of the impedance of the second impedance means being selectively adjustable to vary the amount of current from the second source flowing in the one deflection coil of the second pair and wherein the neck twist compensating means further includes third and fourth rectifiers and second variable resistance means, the third rectifier being connected to one of the second pair of deflection coils, the second rectifier being connected to the other of the second pair of deflection coils, and the second variable resistance means being connected in series between terminals of like polarity at the third and fourth rectifiers and further connected to the second source of deflection voltage for supplying a net rectified current of a predetermined polarity to the second pair of deflection coils.
